SAFETY RAZOR AND BLADE MAGAZINE
THEREFOR

Warner Steinbach, Maplewood, N. J.

Application January 4, 1945, Serial No. 571,260

3 Claims. (Cl. 30—40)

1

This invention relates to a magazine for double-edge safety razor blades and means whereby such a magazine can be mounted on the razor to inject a new blade while simultaneously ejecting a dull one. Magazines for double-edge blades have been proposed, but always, so far as I am aware, for use in connection with razors of special construction which are unnecessarily complicated and expensive or which cannot be used with the general run of three-hole or slotted blades obtainable on the market. My primary object is to simplify and improve such magazines and to provide a razor for use in connection therewith, which although modified to receive the magazine in blade injecting-ejecting position is, nevertheless, capable of use with any standard blade in the time-honored manner. A further object of my invention is to provide improved means for preventing contact between the magazine and the cutting edges of the blades, both before and during the blade-discharging operation. Another object of my invention is to provide simple and effective means for locking the magazine in blade-feeding position on the razor so that a new blade can be accurately and quickly fed into shaving position while its dull predecessor is being ejected.

As the standard double-edge safety razor is provided with a central threaded stud or rod depending from its cap or outer clamping plate, and also with blade-locating pins or medial bar, likewise depending from the cap, it is impossible to feed a conventional blade into position between the cap and guard plate without a complete separation of the two. As this is not feasible the blade must be provided with a medial slot, slightly wider than the thickest stud, rod, pin or bar, and left open at one end so that it can be fed into shaving position, open end foremost, straddling all obstructions—and likewise be ejected closed end foremost. I stack my open-slotted blades in a magazine with the open slots all facing the discharge end, and urge them upward against the top of the magazine by means of a spring-pressed plate. A slide movable in a longitudinal slot in the top and provided with an external knob engages the rear end of the topmost blade and, on being moved forward, discharges it through a passage defined by the upper edge of the front wall of the magazine and the top.

It is essential that the cutting edges of the blades never engage any part of the magazine or razor. To this end, I provide the rear corners of the magazine with vertical guide blocks cooperating with projections on the rear edges of the

2

blades to hold the rear of the cutting edges out of contact with the side walls of the magazine, and also provide a vertical guide rib along the inner face of the front wall extending within the blade slots to hold the forward ends of the cutting edges away from the side walls. As the forward guide must stop short of the discharge passage and so cannot act on the topmost blade at any time, and as the rear guides cannot function on the topmost blade while it is being discharged, I provide other means for insuring that the cutting edges of the topmost blade do not strike the walls of the magazine either before or during discharge: a spring tongue extending upward from the pressure plate passes through the slots near their forward ends and, bearing against the top of the magazine, serves to center the topmost blade and hold its forward cutting edges out of contact with the side walls of the magazine at all times, and the slide is shaped to fit snugly between the projections on the rear edge of the topmost blade. These devices serve to center the topmost blade at all times—before and during discharge—and prevent any contact of the cutting edges with the magazine.

To mount my magazine on the razor I provide tongues on the former engaging guideways on the under face of the guard plate, and to insure proper alignment I provide a projection on the magazine which enters a corresponding recess in the cap and is locked in position by turning the razor handle to separate the cap and the guard. This lock places the discharge slot of the magazine in alignment with the slightly flexed dull blade in the razor so that movement of the slide toward the razor feeds a new blade into shaving position while simultaneously ejecting the dull one.

I have illustrated and described certain preferred embodiments of my invention in the accompanying drawings. No doubt others also could be devised within its purview and these, too, are embraced within my claims.

In these drawings:

45 Figure 1 is a front elevation of the razor and magazine of my invention shown in blade-feeding relationship.

Figure 2 is a perspective view of the magazine detached from the razor,

50 Figure 3 is a plan view of the razor and magazine shown in Figure 1,

Figure 4 is a vertical section on an enlarged scale taken along line 4—4 of Figure 3,

Figure 5 is a horizontal section taken along line 5—5 of Figure 1, looking down,

Figure 6 is a horizontal section taken along line 6—6 of Figure 1 looking up.

Figure 7 is a bottom view of the magazine top or cover.

Figure 8 is a top view of the pressure plate, 5 Figure 9 is a vertical section through the plate taken along line 9—9 of Figure 8,

Figure 10 is a top view of the guard plate,

Figure 11 is an end view of the guard plate showing the guideways for the magazine tongues, 10

Figure 12 is a transverse section on a still further enlarged scale taken along line 12—12 of Figure 4,

Figure 13 is a similar section taken along line 13—13 of Figure 4,

Figure 14 is a transverse section on the same large scale taken along line 14—14 of Figure 3 and showing the condition of cap, guard and dull blade when the magazine is locked in block-feeding position,

Figure 15 is a longitudinal section through the magazine taken along line 15—15 of Figure 16, but on a smaller scale, similar to that of Figure 4, but showing a modified form of blade-centering guide and also showing the slide toward the end of its blade-discharging movement,

Figure 16 is a transverse section taken along line 16—16 of Figure 15 and

Figure 17 is a detail showing in perspective the relative positions of the new incoming blade 30 and the dull outgoing one.

In these drawings I have illustrated a conventional safety razor of the Gillette type, modified as I shall describe presently and comprising a cap 20, a guard plate 21 and a handle 22, the guard plate being permanently but rotatably mounted on the handle in the usual way. The cap is provided with the conventional blade-locating pins 23, extending through holes 24 in the guard plate, and with a central threaded stud 25 which enters a threaded socket 26 in the handle. The cap and guard plate are drawn together to clamp and flex a blade between them by turning the handle clockwise with respect to the guard plate and the two clamping members are separated by turning the handle counter-clockwise.

In Figure 1 I have illustrated a magazine 27 mounted in blade-feeding position on the razor by means which I shall describe presently, but first I shall describe the magazine itself and its blade-feeding mechanism.

The magazine proper comprises a casing having a bottom 29, top 31, side walls 32, back wall 33 and front wall 34. I have shown the top 31 provided with depending flanges fitting over the side and rear walls, but this is not important and other means for constructing the casing may be employed. Within the magazine at its rear corners, I provide a pair of vertical guide blocks 35, and at the middle of the front wall 34 a vertical guide rib 36 whose function it is to center the blades. A horizontal blade-discharge passage 37, as deep as the thickness of a blade, is provided between the top edge of the front wall 34 and the top 31. Extending forwardly from the front wall 34 are a pair of tongues 38 adapted to cooperate with guideways on the guard plate, and extending forwardly from the top 31 is a projection 39, dovetail in cross section, which is adapted to engage a correspondingly shaped recess in the cap of the razor to form a wedge lock. Slidably mounted within a longitudinal slot 41 in the top 31 is a slide 42 provided with an external knob 43. Forward movement of the 75

slide along the slot 41 serves to expel a blade, in a manner to be described presently.

Supported upon the bottom of the magazine are four coil springs 44 which support a pressure plate 45 which, in turn, supports a stack of blades 46. These blades, as illustrated in Figures 5 and 17 are double-edge blades, each provided with a longitudinal slot 47 open at one end and closed at the other. The rear edge of each blade is provided with two rearwardly extending projections 48. Extending upward from the plate 45 is a spring tongue 49 which passes through the slots 47 of the stacked blades and, pressing against the underface of the top 31 of the magazine, acts 15 to center the blades, including the topmost one, particularly at their forward or open-slotted ends. The rear projections 48 on the blades engage the corner blocks 35, as illustrated in Figures 5 and 6, and the guide rib 36 extends into the blade slots, 20 and thus the blades are spaced from the side walls of the magazine and their cutting edges protected.

The slide 42 is just wide enough to fit within the projections 48 along the rear edge of each blade. Thus when the slide has been retracted to its rearmost position as shown in Figures 4, 5 and 6, it fits between the projections 48 of the topmost blade, which is pressed against the top 31 by the pressure plate and is in alignment with the slide. When the slide is moved to the left through manipulation of the knob 43, the topmost blade is disengaged from the stack and moved forward through the discharge passage 37, lower blades being held back by the forward wall. This movement is facilitated by the provision of ribs 50 on the lower face of the top 31. During the discharge movement of the topmost blade, its rear end is centered with reference to the side walls of the magazine by the action of the slide 42 fitting within the projections 48. Meanwhile, the forward end of the blade is centered by means of the spring tongue 49. When the end of the slot 47 reaches the tongue 49, the tongue is depressed to permit overriding by the blade and from this point on the blade must be centered by the slide itself, but this presents no difficulties because by this time most of the blade has left the magazine. The slot 41 extends forward beyond the front wall 34 and thus enables the slide to discharge a blade completely. When one blade has been discharged, the slide is returned to its initial position at the rear of the magazine where it is held in readiness to discharge another.

I shall now describe the means for mounting and locking the magazine upon the razor. Guideways for the tongues 38 are formed at each end of the guard plate 21 by cutting strips of metal from the guard plate and bending them downwardly and inwardly to form the angles 51. This is a simple and inexpensive method of forming guideways, although other means might be employed, or separate guideways mounted on the underface of the guard plate. As shown in Figures 2 and 14, the tongues 38 are laterally tapered slightly to make a snug fit between the horizontal flanges of the angles 51 and the lower arcuate face of the guide plate which, between them, define the guideways. The magazine is now mounted on the razor, but not locked there. In order to lock the magazine in blade-feeding position, I provide a recess 52 at each end of the cap 20, which recess is provided with upwardly flaring side walls designed to receive the correspondingly shaped projection 39 from the

end of the magazine top, as illustrated best in Figure 14.

When an old dull blade is to be ejected from the razor and replaced by a new sharp one, the cap and guard plate are moved toward each other by turning the handle to the right. Thereupon the magazine is mounted upon that end of the guard plate underlying the open-slotted end of the dull blade by inserting the tongues 38 within the guideways and pressing the magazine home until its front wall 34 abuts against the adjacent edge of the guide plate. With the parts in this position the projection 39 overlies one of the recesses 52. In order to lock the magazine on the razor, the handle is then turned counterclockwise to separate the guard plate and cap, thus firmly seating the projection 39 within the adjacent recess 52, and releasing the clamping pressure on the dull blade. We now have the dull blade only slightly flexed between the spaced cap and guard plate, as illustrated in Figures 14 and 17, and the parts are in readiness for the blade injecting-ejecting operation. Movement of the slide to the left discharges a sharp blade from the magazine. The forward end of this blade engages the adjacent end of the flexed dull blade, as illustrated in Figure 17, and ejects the latter from the razor as the new blade takes its place. Now the handle is turned clockwise to clamp the new blade and flex it into shaving position. This releases the cam lock and permits withdrawal of the magazine.

In Figures 15 and 16, I have illustrated a modified form of blade-centering means. Instead of the fixed guide rib 36 and the spring tongue 49 extending upwardly from the plate 45, I combine the two and provide the inner face of the forward wall 34 with a spring-pressed guide 54 which normally presses against the top of the magazine and centers all of the blades including the topmost. Like the spring tongue 49, this guide 54, although normally pressing against the under surface of the top 31 of the magazine, may be depressed to permit overriding by the blade being discharged.

In actual practice I would construct my magazine of plastic or some light cheap metal, mount the blade stack within it at the factory and make

it nonrefillable. Thus the whole would constitute a blade package to be discarded when emptied of its contents—the blades.

Although the razor used with my magazine must be adapted to receive it, as shown and described, nevertheless it is not so different from the ordinary Gillette-type razor as not to be usable in the regular way with regular blades.

I claim:

- 10 1. A magazine for holding a stack of blades each having an open-ended longitudinal slot and having a blade discharge passage between its top and forward wall, means at the discharge end of the magazine for mounting it on the guard plate of a safety razor, a projection forming part of a lock extending from the magazine at its discharge end, and means for discharging blades one by one.
- 15 2. Apparatus for feeding razor blades into shaving position comprising a razor blade magazine having a discharge passage, a safety razor having clamping members for a blade, means for mounting the magazine on one of the clamping members with its discharge passage facing the razor, interlocking means on the magazine and the other clamping member and means for separating the clamping member to lock the magazine in blade-feeding relation to the razor.
- 20 3. The combination of a double-edge safety razor comprising guard plate and cap, a recess in the cap, a guide on the guard plate, a magazine for holding a stack of blades, and having a blade discharge passage at one end, an extension on the magazine cooperating with the guide on the guard plate to mount the magazine on the razor, a projection on the magazine at its discharge end extending into the correspondingly shaped recess in the cap, means for discharging blades one by one, from the magazine and feeding them between the guard plate and cap while ejecting a dull blade from the razor, and means for separating the guard plate and cap to lock the magazine on the razor with the discharge passage in alignment with the blade-receiving space between guard plate and cap, and release the pressure on the dull blade.
